UNITED STATES PATENT OFFICE.

SAMUEL D. IRWIN, OF FLOYDADA, TEXAS.

VACUUM-DISTRIBUTER FOR INTERNAL-COMBUSTION ENGINES.

1,297,855.

Specification of Letters Patent. Patented Mar. 18, 1919.

Application filed August 28, 1918. Serial No. 251,776.

To all whom it may concern:

Be it known that I, SAMUEL D. IRWIN, a citizen of the United States, residing at Floydada, in the county of Floyd and State 5 of Texas, have invented certain new and useful Improvements in Vacuum-Distributors for Internal-Combustion Engines; and he does hereby declare the following to be a full, clear, and exact description of the invention, such as will enable others skilled in 10 the art to which it appertains to make and use the same, reference being had to the accompanying drawings, and to the letters and figures of reference marked thereon, which 15 form a part of this specification.

While relating generally to internal combustion engines, my invention relates more specifically to vacuum-distributors for the type of vacuum-energized make-and-break 20 spark-plugs shown, for instance, in United States Patent to Herbert G. Irwin, No. 1,268,719, dated June 4, 1918, for an improvement in "vacuum-energized make-and-break spark-plug."

25 The fundamental object of my invention is to provide a vacuum-distributer for this purpose which shall be automatic in operation, and which shall be timed so as to create a vacuum in the spark-plugs successively, at 30 the proper periods.

Another object is to provide a vacuum-distributer embodying novel means for lubricating the working parts thereof.

Another object is to provide the vacuum-distributer with a "breather," whereby outside air may pass through the vacuum-distributer to the crank-case of the engine, the "breather" being constructed so as to prevent the ingress of dirt and impurities to the 40 vacuum-distributer, and to prevent egress from the latter of the oil-mist emanating from the crank-case with which the distributor communicates.

Other objects relating to specific improvements going to make up the ultimate perfection of the entire device will appear as the specification proceeds and the nature of the invention more fully appears.

With these objects in view, the invention, 50 generally stated, resides in a vacuum-distributing apparatus embodying a rotating distributing-member communicating with the intake-pipe of the intake-manifold and controlled by the engine-shaft so that the vacuum-energized spark-plugs may be placed successively in communication with said in-

take-pipe in timed relation with the movements of the engine, and the spark-plugs thereby energized.

The invention resides more specifically in 60 the peculiar construction, combination and arrangement of parts of a vacuum-distributing mechanism, as will be hereinafter fully explained.

The accompanying drawings, forming 65 part of my specification, disclose an illustratory concrete embodiment capable of carrying out the underlying principles of my invention. Like reference-characters designate corresponding parts throughout the 70 several views. The several views of the drawings may be briefly described as follows:

Figure 1 is a view in side elevation of my device in operative position upon an internal-combustion engine;

Fig. 2 is a central vertical sectional view through my device, the lower part of the shaft of the rotating distributing-member being broken away; and

Fig. 3 is a horizontal sectional view, on the line 3—3, Fig. 2, looking in the direction of the arrows.

Referring, now, in detail to the drawings:

1 designates a support, formed as a pipe, 85 appropriately provided with an elbow 2 having a lateral, circumferential flange 3 provided with openings 4, through which may pass securing means, such as screws, for fastening the support to the engine crank-case 90 A around an opening in the wall thereof, whereby the pipe 1 communicates with the interior of said crank-case.

5 designates a casing or shell, annular in cross section, which is rotatably supported 95 by the bracket 1 in any suitable manner, in this instance by means of a depending, tubular stem 6, annular in cross section and bearing against the inner surface of the bracket 1, as shown in Fig. 2. The bottom 100 of the casing 5, at the top of said stem, bears upon the top of the bracket 2. Said stem may be conveniently provided with a spider, comprising spokes 7 radiating from a hub 8, constituting a bearing for a rotating shaft 105 9 extending axially of the bracket 1 and transversely through the elbow 2 thereof, and being provided, at its lower end, with a pinion or bevel gear 10 meshing with a complementary gear 11 on the engine-shaft B, or 110 some rotating shaft geared to the engine-shaft and timed so as to rotate at the same

speed. Said shaft 9 is provided with a circumferential flange 12 bearing upon the top of the hub 8, as shown in Fig. 2, and preventing downward displacement of the shaft. 5 The flange 12 is provided with an arm 13 in the same plane as the flange, and constituting a shelf supporting a sliding shoe 14, constituting the rotating distributing-member, to be more particularly hereinafter described. 10

By referring to Fig. 2, it will be noticed that the shaft 9 is solid from the bottom thereof up to a point desirably coincident with the flange 12, thence the shaft is hollow 15 up to the top thereof, as shown at 15. The hollow portion of the shaft is provided with a longitudinally-extending slot 16. Communicating with said slot is a hollow trunk 17 (see Fig. 3) projecting from and carried 20 by the hollow portion of the shaft 9, and preferably coextensive with the slot 16. One wall of the trunk 17 is slotted, as shown at 18, this slot being preferably of the same length as the slot 16. Communicating with 25 the slot 18 and consequently with the interior of the trunk 17 preferably through the medium of a hollow nipple 19 suitably secured to the trunk 17, as by screws 20, is one end of a cross-sectionally arcuate tunnel 21, the other end whereof communicates, preferably through a similar nipple 22, with a slot 23 in the shoe or distributing-member 14.

Rising from the sides of the shelf 13 are 30 walls 24, 24 connected, at their top, by a bridge 25, similar to the shelf 13 and carried by the shaft 9. Thus, an open-ended box, as it were, is formed, whose top is the bridge 25, whose bottom is the shelf 13, and whose 35 sides are the walls 24, 24; and projecting into and guided by this box is the shoe or distributing member 14, provided with one or more sockets 26 (in this instance, two are shown), in each of which is a coiled spring 40 45 27 bearing, at one end, against the exterior of the shaft 9, and serving to maintain the rotating shoe in frictional engagement with a cylindrical and preferably removable lining 28 to the casing 5.

50 As shown, the shoe 14 is provided with a lateral skirt 14', which is hollowed out, on one face thereof, as shown, to provide a space or chamber 29 between the skirt and the lining 28.

55 The lining 28 and the casing 5 are provided with coincident ports 30, 31, respectively. Each port 31 communicates with a hollow protuberance 32 carried by the shell or casing 5. The top of each protuberance 60 is interiorly threaded, as shown in Fig. 2; and screwed into such threaded end is the threaded end of a coupling 33. Secured in the coupling is one end of a preferably flexible pipe 34 leading to one of the vacuum-65 energized spark-plugs C of the engine, these

spark-plugs being of the type which is shown, for instance, in said U. S. Patent, No. 1,268,719.

Disposed on top of and removably secured to the casing 5 is a hood or cover 35 provided with one or more circumferentially-extending openings, in which are inserted reticulated screens 36, of fine mesh. The hood is also provided with an axial opening, as clearly shown in Fig. 2, through which the 75 top of the shaft 9 projects.

Loosely encircling the upper end of the shaft 9, and projecting through the cap 35, is a sleeve 37, provided, at its lower end, with a circumferential flange 38 supported 80 upon a circumferential flange 39 carried by the shaft 9.

Extending radially upward from the flange 38 are a plurality of arms 40, having angled ends 41, through which loosely project bolts 42, whose threaded ends are screwed into bosses 43 depending from the inner surface of the cap 35. Encircling the sleeve 37 and bearing, at one end, against the top of the cap 35 and, at its other end, 90 against the flange 38 is a coiled expansion spring 44, exerting a downward stress upon the sleeve 37 and serving to maintain the same with its flange 38 in frictional engagement with the flange 39 of the shaft 9. 95

The sleeve 37 is provided, at its top, with a thread-nipple 45 on which is screwed a hollow coupling 46, with which communicates a preferably flexible tube 47 leading to the pipe D between the carburetor E and 100 the intake-manifold F of the engine.

Carried by the shell or casing 5 is a lever 48, by which the casing may be partially rotated, as desired, to advance or retard the spark or firing-time of the plugs C. 105

In a device of this nature, it is important that the moving parts be properly lubricated at all times, while in operation. To this end, therefore, the casing 5 communicates, through the tubular bracket 1, with the interior of 110 the crank-case A of the engine, and is provided with the reticulated screens 36 in the openings in the cover 35, through which outside air passes in and out of the crank-case A, when the engine is in operation. 115 The screens prevent dirt and impurities from entering the shell or casing 5, and also tend to prevent the oil-mist, which emanates from the crank-case A and passes up through the tubular bracket 1 into the shell 120 5, from escaping from the latter, as it would do if such openings in the cover 35 were not screened. Said oil-mist or vapor settles on the working parts within the shell 5 and properly lubricates the same at all times. 125

In operation, the device of my invention is so timed that, when the periodic vacuum occurs in the pipe D, in the operation of the engine, the shaft 9 will have been rotated so as to bring the shoe or distributing-member 130

14 so that the space or chamber 29 communicates with the registering ports 30, 31 and the corresponding protuberance 32, whereupon the suction is communicated to the corresponding spark-plug C from the intake-pipe D, through tube 47, the hollow portion 15 of the shaft 9, the slot 16, the tunnel 21, the port 23 of the distributing-member 14, the chamber 29, the registering-ports 30, 31 10 and corresponding protuberance 32, and tube 34. The vacuum-impulse thus produced in the vacuum-energized spark-plug operates the spark-plug, producing a spark and firing the charge in the corresponding engine-cylinder.

Having thus fully described my invention, the many advantages thereof will be apparent, especially to those skilled in the art to which the invention pertains.

20 I am aware that many variations, especially in matters of structural detail, may be made in the physical embodiment of the invention herein disclosed; but it is to be understood that I am entitled to all mechanical equivalents, and that all changes which fall within the scope of the appended claims, when construed in accordance with the importance of this invention, do not constitute a departure from the spirit of the invention.

30 Having thus fully described my invention, what I claim as new and desire to secure by Letters Patent is:

1. In an internal-combustion engine, the combination, with vacuum-energized spark-plugs, of mechanism communicating with said spark-plugs and controlled by the engine-shaft for automatically establishing a vacuum in said spark-plugs, successively.

2. In an internal-combustion engine, the combination, with vacuum-energized spark-plugs, of mechanism communicating with said spark-plugs and timed so as to automatically establish a vacuum in said spark-plugs, successively.

45 3. In an internal-combustion engine, the combination, with vacuum-energized spark-plugs, of mechanism communicating with said spark-plugs and including a rotatable vacuum-distributing member, for automatically establishing a vacuum in said spark-plugs, successively.

4. In an internal-combustion engine, the combination, with vacuum-energized spark-plugs, of mechanism communicating with said spark-plugs for automatically establishing a vacuum therein, successively, said mechanism including a casing, and a revolute vacuum-distributing member in said casing.

60 5. In an internal-combustion engine, the combination, with vacuum-energized spark-plugs, of mechanism for automatically establishing a vacuum therein, successively, including a casing, a revolute vacuum-distributing member in said casing, and hol-

low connections between said casing and said spark-plugs.

6. In an internal-combustion engine, the combination, with vacuum-energized spark-plugs, of mechanism for automatically establishing a vacuum therein, successively, including a casing, a revolute vacuum-distributing member in said casing, hollow connections between said casing and said spark-plugs, and a rotating shaft carrying said vacuum-distributing member.

7. In an internal-combustion engine, the combination, with the engine-shaft and with vacuum-energized spark-plugs, of mechanism for automatically establishing a vacuum in said spark-plugs, successively, including a casing, a revolute vacuum-distributing member in said casing, hollow connections between said casing and spark plugs, and a rotating shaft carrying said vacuum-distributing member and geared to the engine-shaft.

8. In an internal-combustion engine, the combination, with the crank-case of the engine and with vacuum-energized spark-plugs, of mechanism for automatically establishing a vacuum in said spark-plugs, successively, including a casing, a hollow support for said casing and communicating therewith and with said crank-case, a revolute vacuum-distributing member in said casing, and hollow connections between said casing and spark-plugs.

9. In an internal-combustion engine, the combination, with vacuum-energized spark-plugs, of mechanism for automatically establishing a vacuum in said spark-plugs, successively, including a casing, a revolute vacuum-distributing member in said casing and outwardly springpressed against the casing, and hollow connections between said casing and spark-plugs.

10. In an internal-combustion engine, the combination, with vacuum-energized spark-plugs, of mechanism for automatically establishing a vacuum in said spark-plugs, successively, comprising a casing, a support rotatably supporting said casing, a vacuum-distributing member rotatably supported in said casing, and hollow connections between said casing and spark-plugs.

11. In an internal-combustion engine, the combination, with vacuum-energized spark-plugs and with the crank-case of the engine, of mechanism for automatically establishing a vacuum in said spark-plugs, successively, comprising a casing, a hollow support for said casing communicating therewith and with said crank-case, a vacuum-distributing member rotatably supported in said casing, and hollow connections between said casing and spark plugs.

12. In an internal-combustion engine, the combination, with vacuum-energized spark-plugs and with the crank-case of the en-

gine, of mechanism for automatically establishing a vacuum in said spark-plugs, successively, comprising a casing having screened openings, a hollow support for 5 said casing communicating therewith and with said crank-case, a vacuum-distributing member rotatably supported in said casing, and hollow connections between said casing and spark-plugs.

- 10 13. In an internal-combustion engine, the combination, with vacuum-energized spark-plugs and with the intake-pipe of the intake-manifold of the engine, of mechanism for automatically establishing a vacuum in said 15 spark-plugs, successively, comprising a casing communicating with said intake-pipe, a vacuum-distributing member rotatably supported in said casing, and hollow connections between said casing and spark-plug 20 and successively placed in communication with said intake-pipe by said vacuum-distributing member in the rotation thereof.

14. In an internal-combustion engine, the combination, with vacuum-energized spark-plugs and with the intake-pipe of the intake-manifold of the engine, of mechanism for automatically establishing a vacuum in said spark-plugs, successively, comprising a casing communicating with said pipe, a 25 vacuum-distributing member rotating in frictional contact with the wall of said casing and provided with a face hollowed out to provide a chamber between said face and said casing, and hollow connections between 30 said casing and spark-plug.

15. In an internal-combustion engine, the combination, with vacuum-energized spark-plugs and with the intake-pipe of the intake-manifold of the engine, of mechanism for 40 automatically establishing a vacuum in said spark-plugs, successively, comprising a cas-

ing, a rotatable shaft extending axially through said casing and hollow in the portion thereof within said casing, said hollow portion communicating with said casing, a 45 hollow connection between said intake-pipe and the hollow portion of said shaft, a vacuum-distributing-member rotatably supported in said casing, and hollow connections between said casing and said spark-plugs. 50

16. In an internal-combustion engine, the combination, with vacuum-energized spark-plugs, of mechanism for automatically establishing a vacuum in said spark-plugs, 55 successively, comprising a casing, a support upon which said casing is rotatably mounted, a manually-operable lever carried by said casing for manually rotating the same, a vacuum-distributing member rotatably 60 supported in said casing, and hollow connections between said casing and said spark-plugs.

17. In an internal-combustion engine, the combination, with vacuum-energized spark-plugs and with the engine crank-case, of mechanism for automatically establishing a vacuum in said spark-plugs, successively, comprising a casing, a hollow support for 65 said casing and communicating therewith and with said crank-case, said casing including a removable cover having screened openings therein, a vacuum-distributing member rotatably disposed in said casing, and hollow connections between said casing 70 and said spark-plugs.

In testimony whereof I hereunto affix my signature in presence of two witnesses.

SAMUEL D. IRWIN.
